MANUALLY OPERABLE OBJECT PROPELLING
AMUSEMENT DEVICE

Louis F. Guss, Green Lake, Wis.

Application December 6, 1957, Serial No. 48,821

Term of patent 14 years

(Cl. D34—15)

Fig. 1 is a side elevational view of a manually operable object propelling amusement device, embodying my new design, the opposite side being substantially a mirror image thereof;

Fig. 2 is a front elevational view of the same;

Fig. 3 is a rear elevational view thereof;

Fig. 4 is a top plan view of the same; and

Fig. 5 is a bottom plan view thereof.

I claim:

The ornamental design for a manually operable ob-

ject propelling amusement device, substantially as shown and described.
